UNITED STATES PATENT OFFICE

CHARLES E. WILCOX, OF LONG BEACH, CALIFORNIA

ELEVATOR

Application filed May 31, 1930. Serial No. 458,406.

This invention relates to a device for handling well drilling equipment and relates more particularly to an elevator for handling casing, drill pipe, etc. It is a general object of this invention to provide a safe, dependable, and practical elevator for handling well drilling tools and equipment.

Elevators are employed in well drilling rigs to handle various tools and equipment such as drill pipe, well casing, etc. It is important that elevators of this character be strong and durable so that they are safe to operate and that they be constructed so as to be easily and quickly arranged in position around the part to be handled. Elevators are often swung into place around the work while in motion and sometimes the gate or door of the elevator is not properly latched before the elevator is raised to engage a coupling, or the like, on the pipe or work. When this occurs the work or pipe may be raised some distance and may then become displaced from the elevator and fall to the floor of the derrick.

It is an object of the present invention to provide an elevator that is particularly safe and dependable to operate and which may be easily and conveniently arranged in position around the work.

It is another object of this invention to provide an elevator in which the work embracing and retaining parts are automatically swung or operated together to a closed or latched position through engagement with the work in the event that they are not properly latched together prior to actuation of the elevator.

It is another object of this invention to provide an elevator of the character mentioned in which the means for automatically operating the work engaging sections together to the latched position does not interfere with the operation of the elevator and does not complicate or weaken the construction.

Another object of the present invention is to provide an elevator of the character mentioned in which the means for automatically operating the work embracing or retaining sections together is entirely automatic in its

operation and does not require manual setting or adjusting.

It is a further object of this invention to provide an improved latch for releasably retaining the gate of an elevator, or the like, in the closed position.

Other objects and features of my invention will be best and more fully understood from the following detailed description of a typical form and application of the invention, throughout which description reference is had to the accompanying drawings, in which:

Fig. 1 is a top or plan view of the elevator provided by this invention illustrating it in operating position around a drill pipe, or the like. Fig. 2 is a view similar to Fig. 1 illustrating the gate section in the open position. Fig. 3 is a side elevation of the elevator showing the gate in the closed position. Fig. 4 is a side elevation of the elevator illustrating the gate in the open position. Fig. 5 is an enlarged vertical detailed sectional view taken as indicated by line 5-5 on Fig. 1. Fig. 6 is a vertical detailed sectional view taken as indicated by line 6-6 on Fig. 5. Fig. 7 is a vertical detailed sectional view taken substantially as indicated by line 7-7 on Fig. 6, being a view illustrating the gate closing means in the actuated position. Fig. 8 is an enlarged vertical detailed sectional view taken as indicated by line 8-8 on Fig. 1. Fig. 9 is an enlarged vertical detailed sectional view taken as indicated by line 9-9 on Fig. 3. Fig. 10 is a horizontal detailed sectional view taken as indicated by line 10-10 on Fig. 9, and Fig. 11 is an enlarged view of the cam means for automatically closing the gate.

The invention is applicable, generally, to elevators such as are used in well drilling derricks for handling drill pipe, casing, and the like. The invention is particularly suited for embodiment in the side door type of elevator and throughout the following disclosure the invention will be described as embodied in a side-door type of elevator for handling drill pipe. It is to be understood that the invention is not to be taken as limited to the particular form or application about to be described but that it is to be taken as in-

cluding any features or modifications that may fall within the scope of the claims.

The elevator construction provided by the present invention includes two main sections, namely, a body section A and a gate section B, a connection C between the sections A and B whereby they may be swung or operated together to embrace a drill pipe P, means 10 for releasably holding the sections A and B together around the pipe P, and means 11 for automatically operating the sections A and B to the latched or closed position around the pipe.

The section A is the main or body section of the elevator and is provided with a recess or open-sided opening 12 for receiving the pipe P. The walls of the opening 12 are curved or rounded to conform to the configuration of the pipe. The body section A is preferably made comparatively heavy and may be in the nature of an integral member. The upper side 13 of the body section A is preferably made flat to effectively receive or support a coupling 14, or the like, on the pipe P.

Means may be provided in connection with the body section A for carrying bails 15 for supporting or suspending the elevator. In the particular case illustrated the body section A is provided at its opposite sides with bail ears 16. There may be two vertically spaced ears 16 projecting from opposite sides of the section A. Pins or bolts 17 may be arranged between the outer parts of each pair of bail ears 16 to prevent displacement of the bails 15 from the ears. The bolts 17 may be slidably arranged through openings 18 in the upper ears 16 and may have their lower ends screw threaded into openings 19 in the lower ears. Laterally projecting pins 20 may be provided on the bolts 17 to fit into or cooperate with bayonet slots 21 in the lower sides of the upper ears 16 to permit the insertion and removal of the bails 15 from between the ears.

The section B is in the nature of a closure or gate for the open side of the body opening 12 and is adapted to embrace or engage the pipe P to retain it in the opening. The gate section B is adapted to be releasably held in the closed pipe engaging position by the means 10. The section B may be substantially semi-circular in plan configuration and is provided with a curved inner side 22 for engaging the pipe P. A suitable handle 23 may be provided on the outer side of the gate section B.

The connection C between the sections A and B is in the nature of a pivotal connection and is such that the sections may be swung together to engage around or embrace the pipe P. An end of the gate section B is pivotally connected to the body section A adjacent one side or edge of the body opening 12. The end of the gate section B and the body

are provided with cooperating or overlapping parts and a pivot pin 24 extends through openings in the overlapping parts to pivotally connect the sections. In the case illustrated the end of the section B is provided with two vertically spaced lugs or tongues 25 fitting into spaced sockets or openings 26 in the section A. The ends of the tongues 25 and the inner walls of the openings 26 may be rounded or curved so that the gate section B may be readily pivoted on the pivot pin 24.

The means for releasably holding the sections A and B together in position around the pipe P is in the nature of a releasable latch means for releasably connecting the free or outer end of the gate section B with the body section A.

In accordance with the broader principles of the invention any suitable form of latch may be embodied in the elevator for releasably retaining the gate section B in the closed position around the pipe P. In the drawings I have illustrated an improved latch 27 for latching the gate section B in the pipe retaining position. The latch 27 includes a vertically extending body portion 28 to cooperate with a latch catch or lug 29 on the gate section B, and laterally projecting arms 30 projecting from the portion 28 and pivoted to the body section A. The arms 30 may project inwardly from the opposite ends of the portion 28 and are arranged through horizontal openings 31 in the body section A. The arms 30 are in the nature of lever arms and are pivoted to the body intermediate their ends on a pivot pin 32 extending vertically through the body. The horizontal openings 31 in the body are sufficiently long to permit the desired limited pivoting of the arms 30 so that the latch may cooperate with and be released from the lug 29.

Means is provided for yieldingly holding the latch in the closed or latching position and for automatically operating the latch upon actuation of the gate section B to the closed position. Springs 33 are arranged under compression between the arms 30 and the walls of the openings 31 to yieldingly hold the latch in the closed position. The forward side of the lug 29 is beveled to cooperate with the vertical portion 28 of the latch and to cause swinging of the latch upon closing of the gate, while the rear side of the lug 29 is flat to effectively cooperate with the inner side of the portion 28 to hold the gate section B in the closed position. A handle 35 may be provided on the portion 28 of the latch to facilitate releasing of the latch.

In accordance with the preferred form of the invention the body section A and the outer or free end of the gate section B are provided with cooperating parts to distribute the weight of the pipe P on the sections A and B when the elevator is carrying the pipe. The free end of the gate section B and the

body section A are provided with parts which overlap or fit together when the gate section is in the closed position. In the particular form of the invention illustrated in the drawings, the body section A is provided with recesses 36 to receive the end portion of the gate section B and is provided with a lug 37 between the recesses 36 to fit into a recess 38 in the outer or free end of the gate section B. The lug 38 cooperates with the outer end of the gate section B to positively prevent vertical shifting of the gate section when it is in the closed position.

The means for automatically operating or swinging the sections A and B together around the pipe P is operable by or through engagement with a coupling 14 on the pipe P to swing or pivot the gate section B to the closed or latched position. In the preferred form of the invention the means 11 is incorporated in or provided in connection with the pivotal connection C between the sections A and B. When the closing means 11 is provided in connection with the pivotal connection C, the pivot pin 24 is slidable vertically in the openings in the tongues 25 and the body section A.

The means 11 is in the nature of a cam means and includes a cam part 40 on the pivot pin 24 to cooperate with a cam face 41 on a tongue 25 of the gate section B to cause pivoting of the gate section B upon downward movement of the pivot pin 24. A laterally projecting head 42 is provided on the upper end of the pivot pin 24. The head 42 is adapted to be engaged by a coupling 14, or the like, and preferably extends inwardly to or adjacent the edge of the body opening 12. The pivot pin 24 is normally yieldingly held in an up position where the head 42 projects above the upper side 13 of the body by a coiled spring 44 arranged between a plug 45 screw threaded into the pin carrying opening of the body and the lower end of the pin 24. The spring 44 may extend into a longitudinal opening 46 in the lower end of the pin 24. A recess 47 may be provided in the upper side 13 of the body section A to receive the head 42 when it is depressed by the coupling 14 so that its upper side may be flush with the side 13 of the body when the coupling 14 is supported on the elevator.

The cam part 40 is adapted to cooperate with the cam face 41 to close the gate section B upon downward movement of the pin 24 through engagement of the coupling 14 with the head 42. The cam part 40 is in the nature of a longitudinally extending projection on the pin 24. The elongated cam part 40 is slidable in an opening or groove 48 in the body and fits the opening 48 to prevent rotation of the pivot pin 24. The lower end 49 of the cam part 40 is beveled or rounded to cooperate with the cam face 41 to cause

swinging of the gate section B to the closed position upon downward movement of the pivot pin 24. The cam face 41 constitutes a side and the bottom of a notch 41^a formed in the upper side of the uppermost tongue 25. The cam face 41 extends downwardly and inwardly or toward the body section A from the upper side of the tongue 25. The notch 41^a in the tongue 25 is provided with a flat vertical side 50 extending upwardly from the lower edge of the cam face 41 which is adapted to receive the cam part 40 to limit the relative movement between the cam part and the gate section. When the coupling 41 engages the head 42 and causes downward movement of the pivot pin 24 when the gate section B is not in the closed position the cam end 49 of the part 40 rides downwardly along the cam face 41 to cause inward pivoting of the gate section B to the closed position where the latch 27 cooperates with the lug 29 to latch the gate section B in the closed position. A screw 44 may be screw threaded through an opening in the body section A and may extend into a longitudinal groove 45 in the pivot pin 24 to prevent displacement of the pivot pin.

In employing the elevator it is operated to a position where the drill pipe P extends into the body opening 12 and the gate section B is swung to the closed position around the pipe so that the latch 27 automatically retains the gate section in the closed position. The elevator may then be operated upwardly to engage a coupling 14, or the like, and raise or suspend the pipe. In the event that the gate section B is not swung to the latched or completely closed position before raising of the elevator, upward movement of the elevator brings the head 42 into engagement with a coupling 14, or the like. Engagement of the head 42 with the coupling causes depression or downward movement of the pin 24 and causes cooperation between the cam part 40 and the cam face 41. Upon downward movement of the pin 24 the lower end 49 of the cam part 40 operates along the inclined cam face 41 and positively causes closing of the gate section B so that the latch 27 cooperates with the lug 29. The gate section B may be readily released from the latched position by releasing the latch 27. When the gate section B is in the closed position the cam part 40 is in vertical alignment with the lower end of the cam face 41 so that downward movement of the pin 24 when the gate section is in this position does not cause cooperation between the cam part and the face 41.

It is to be noted that the invention provides an elevator that is particularly convenient and safe to operate. The means 11 for automatically swinging the gate section to the closed position does not in any way interfere with the normal handling or operation of the

elevator. The means 11 does not include any parts projecting into the pipe receiving opening of the elevator and does not interfere with free swinging of the gate section B during normal operation. The construction is particularly simple and sturdy and does not require manual setting or adjusting. The means 11 is entirely automatic in its operation and operates independently of the manual actuation of the gate section B.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. An elevator including, two sections adapted to be arranged around an object, and means pivotally connecting the sections and operable by a projecting part on the object to operate the sections together around the object.

2. An elevator including, two sections adapted to be arranged around an object, means pivotally connecting the sections, and means operable through engagement with a projection on the object to swing the sections together around the object, including a cam part on the first-mentioned means operable to engage and operate one of the sections.

3. An elevator including, two pivotally connected sections adapted to be arranged around an object, and means at the pivotal connection between the sections operable through engagement with a projection on the object to operate the sections together around the object.

4. An elevator including, two sections adapted to be arranged around an object, means pivotally connecting the sections, latch means for releasably holding the sections together around the object, and means combined with said pivotal connecting means operable through engagement with a projection on the object to operate the sections together around the object.

5. An elevator including, two sections adapted to be arranged around an object, a pivot pin pivotally connecting the sections, and means operable by a projecting part on the object to operate the sections together around the object, including a cam part on the pivot pin for engaging one of the sections.

6. An elevator including, two pivotally connected sections adapted to be arranged around an object, and means operable by a projecting part on the object to operate the sections together around the object including, a slid able pivot pin pivotally connecting the sections and adapted to be connected by the projecting part, and a cam part on the pin for engaging a section.

7. An elevator including, two pivotally connected sections adapted to be arranged around an object, and means operable by a projecting part on the object to operate the sections together around the object including, a slid able pivot pin pivotally connecting the sections, a cam face on a section, a cam part on the pin for cooperating with the cam face, and means yieldingly holding the pin in a position where it is engageable by the projecting part on the object.

8. An elevator including, two pivotally connected sections adapted to be arranged around an object, latch means for releasably latching the sections together around the object, and means operable by a projection on the object to operate the sections together to actuate the latch means including, a slid able pivot pin pivotally connecting the sections and slidably operable by the projection, and a cam on the pin for engaging a section.

9. In an elevator, two sections, one a body having an opening to receive an object, the other a gate adapted to retain an object in the opening, a pivot pin connecting the sections, the pivot pin being slid able, and means for automatically closing the gate, including a part on the pin adapted to be engaged by a projection on the object, a cam face on the gate, and a cam on the pin for engaging the cam face.

10. In an elevator, two sections, one a body having an opening to receive an object, the other a gate adapted to retain an object in the opening, a pivot pin connecting the sections, the pivot pin being slid able, and means for automatically closing the gate, including a part on the pin adapted to be engaged by a projection on the object, means for yieldingly holding the pin up where the part is engageable by the projection, a cam face on the gate, and a cam on the pin for engaging the cam face.

11. In an elevator, two sections, one a body having an opening to receive an object, the other a gate adapted to retain an object in the opening, a pivot pin connecting the sections, the pivot pin being slid able, latch means for automatically latching the gate closed, and means operable by a projection on the object to operate the gate to a position to actuate the latch means including, a part on the pin engageable by the projection, a cam face on the gate section, and a cam on the pin to cooperate with the cam face.

12. An elevator including, two pivotally connected sections adapted to be arranged around an object, and means operable by a projecting part on the object to operate the sections together around the object including, a slid able pivot pin pivotally connecting the sections, a cam face on a section, a cam part on the pin for cooperating with the cam face, and means yieldingly holding the pin in a po-

sition where it is free of the cam face and where it is engageable by the projecting part on the object.

5 In witness that I claim the foregoing I have hereunto subscribed my name this 23d day of May, 1930.

CHARLES E. WILCOX.
